UNITED STATES PATENT OFFICE.

ALBERT C. KELLEY AND SWAN A. MURPHY, OF GRADYVILLE, GEORGIA.

RAIL-JOINT.

1,108,371.

Specification of Letters Patent. Patented Aug. 25, 1914.

Application filed June 9, 1914. Serial No. 844,067.

To all whom it may concern:

Be it known that we, ALBERT C. KELLEY and SWAN A. MURPHY, citizens of the United States, residing at Gradyville, in the county 5 of Grady, State of Georgia, have invented a new and useful Rail-Joint, of which the following is a specification.

This invention relates to rail joints, its object being to provide a joint which obviates the necessity of using nuts and bolts such as are commonly employed and which not only serves to hold the rails securely together but also prevents pounding by the wheels passing over the joint.

15 A further object is to provide a rail joint, the parts of which cannot be separated by ordinary vibration.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, can be made within the scope of what is claimed, without departing from the spirit of the invention.

In the accompanying drawings the preferred form of the invention has been shown.

In said drawings: Figure 1 is a side elevation of a rail joint embodying the present improvements. Fig. 2 is a section on line 30 A—B Fig. 1. Fig. 3 is a view partly in plan and partly in section of the joint shown in Fig. 1, the section being taken on the line C—D Fig. 2. Fig. 4 is a section on line E—F Fig. 1. Fig. 5 is a perspective 35 view of a portion of one of the members forming a part of the present invention. Fig. 6 is a detail view of one of the pins used in connection with the fish plate. Fig. 7 is a perspective view of a locking member. Fig. 8 is a perspective view of a key for 40 use in connection with the locking member. Figs. 9 and 10 are side elevations of modified forms of rail joints.

Referring to the figures by characters of 45 reference 1 designates rails provided, as ordinarily, with bolt openings 2. Arranged at one side of the rails, to wit, the inner sides thereof, is an ordinary fish plate 3 having openings 4 such as usually provided for bolts. In the present instance, however, these openings, as well as the openings 2 in

the rails are adapted to receive fastening pins 5 one of which has been shown in detail in Fig. 6. Each fastening pin has a head 6 for engaging the outer side of the 60 fish plate 3 while formed within the pin near its other end is a groove 7 extending up to a shoulder 8.

Arranged along the outer side of the rails 1 is a fish plate of novel form, this plate 65 being provided with an upper laterally extending longitudinal flange 9 and an intermediate laterally extending longitudinal flange 10, both of these flanges being located above the usual base flange 11. Openings 70 12 are formed in the upstanding portion of the fish plate, this upstanding portion being indicated generally at 13 and being provided, along its inner side, with a longitudinal rib 14 adapted to fit snugly under the 75 heads of the rails, as shown particularly in Figs. 2 and 4. The intermediate flange 10 is provided in its upper face, with transversely rounded seats 15 registering with the bottom portions of the openings 12 and 80 formed along one side of each of these seats is an angular recess or rabbet 16 extending up to the web or upstanding portion 13. The seats 15 are disposed in pairs, the rabbets or recesses 16 being extended between 85 the seats, as shown in Fig. 5. Interposed between these seats is a groove 17 having, at its inner end, an opening 18 extending all the way through the flange 10.

Where four openings are provided in the 90 fish plate, thus forming two pairs, a vertical reinforcing web 19 is formed between the flanges 9, 10 and 11 and midway between the two pairs of seats 15. Interposed between the webs 19 and the adjacent seats 15 95 of the two pairs are reinforcing webs 20, these webs being located between the upper and intermediate flanges 9 and 10. Back of each web 20 is a spreading element 21 formed integral with the two flanges 9 and 10. That 100 upstanding edge of the spreading element 21 remote from the web 19 is wedge-shaped as shown in Fig. 3, while the inner side of the web 20 is inclined inwardly toward the web 19 and extends slightly past the spreading element 21.

A locking device is insertible between the flanges 9 and 10 above each pair of seats 15. As shown in Fig. 7, this locking device is in the form of a plate 22 having a forwardly 110 extended intermediate portion 23 from which depends a stud 24. A longitudinal shoulder

25 is formed along the top of the plate 22 and has its ends cut off diagonally, as shown at 26. Teeth 27 depend from the plate 22 at opposite sides of the stud 24 and are spaced apart a distance equal to the distance between the seats 15 of each pair.

An elongated wedge 30 is adapted to be inserted longitudinally between the flanges 9 and 10 and above the plate 22 so as to extend back of the shoulder 25, this wedge being provided, at its small end, with a slot 31 extending longitudinally thereof close to its front edge. When the wedge is driven longitudinally into position upon and back of the shoulder 25 and between the flanges 9 and 10, the spreading element 21 will wedge into the slot 31 as hereinafter set forth.

When it is desired to secure two rails together by means of the joint herein described, the fish plate 3 is placed at one side of the rails after which the web 13 of the other fish plate is placed at the other side of the rails, the openings 4 and 12 being disposed in alinement with the openings 2.

25 The pins are then inserted through the two fish plates and the openings 2, the heads of the pins bearing against the fish plate 3 while the grooved portions 7 of the pins will rest within the seats 15. A locking member, such as shown in Fig. 7, is then inserted between the flanges 9 and 10 and above the seats 15. By holding the plate 22 close to the bottom of the flange 9, the stud 24 can slip back into the groove 17 to position directly over the opening 18 whereupon, when the plate 22 is released, the stud 24 will drop into the opening 18 and the teeth 27 will drop into the groove 7 and back of the shoulders 8. Thus withdrawal of the pins from

40 the rails is prevented. The wedge 30 is then inserted longitudinally between the flanges 9 and 10 and above the plate 22, this wedge being so shaped at its bottom as to extend back of the shoulder 25, as shown in Figs. 2 and 4. By driving the wedge 30 longitudinally the slot 31 will be brought to position where the wedging element 21 will enter the same and this wedging element will thus deflect the tongue 32 of the wedge 30 outwardly against the diagonally disposed inner surface of the web 20 which, in turn, will deflect the tongue inwardly, thus causing the tongue to partly wrap about the spreading element 21, as shown in Fig. 3. Consequently accidental withdrawal of the wedge 30 from the fish plate is prevented. Only by forcibly driving the wedge outwardly from the fish plate so as to cause the tongue 32 to bend out of engagement with the element 21, can said wedge 30 be removed from the fish plate. Thus it will be seen that separation of the parts of the joint is prevented unless effected intentionally.

As shown in Fig. 1, the top surface of the flange 9 is inclined upwardly toward its cen-

ter from its ends so that, as the wheels pass over the rails at their meeting ends, they will ride onto this flange 9 and be lifted over the meeting ends of the rails, thus preventing pounding at the joint.

While the structure as described is designed for use in connection with four fastening pins, it is to be understood that with obvious modifications, the joint can be used in connection with either six or eight pins. Where it is used in connection with six pins two fastening devices 22^a are provided, these being the same as the fastening plate 22 hereinbefore described, with the exception that the stud 24' is arranged with two of the teeth 29' at one side thereof and the other tooth 29' at its other side. Where the joint is to be used in connection with eight fastening pins, the plates 22' are the same as those shown in Fig. 7 with the exception that two teeth 29' are located at each side of the stud 24'. These modified structures have been illustrated in Figs. 9 and 10. If desired, the studs 24 and 24' can be provided with cotter pins 33 for holding them against withdrawal from the openings 18.

What is claimed is:—

1. In a rail joint, a fish plate having superposed flanges, one of said flanges being provided with transverse seats registering with apertures in the fish plates, pins insertible transversely through rails and into said apertures and seats, said pins having shoulders, a locking plate insertible between the flanges, separate means carried by the locking plate for engaging the flange thereunder and the respective pins, and means insertible between the flanges and into engagement with the plate for holding said plate against movement relative to the flanges.

2. The combination with abutting rails, of a rail joint including opposed fish plates, superposed flanges extending longitudinally along one of the fish plates, there being transverse seats within the lower one of said flanges and registering with the apertures in the fish plates and rails, pins extending through said apertures and into the seats, said pins having shoulders, a locking plate interposed between the flanges, a stud depending therefrom and insertible into engagement with the lower one of said flanges, teeth depending from the plate and into engagement with the shoulders of the pins, a wedge insertible longitudinally between the flanges and above and back of the plate to secure the plate against movement relative to the flanges, and means integral with the flanges for engaging and spreading the wedge during its insertion between the flanges.

3. The combination with abutting rails, of a rail joint including opposed fish plates, superposed flanges extending longitudinally

along one of the fish plates, there being transverse seats within the lower one of said flanges and registering with the apertures in the fish plates and rails, pins extending through said apertures and into the seats, said pins having shoulders, a locking plate interposed between the flanges, a stud depending therefrom and insertible into engagement with the lower one of said flanges, 5 teeth depending from the plate and into engagement with the shoulders of the pins, a wedge insertible longitudinally between the flanges and above and back of the plate to secure the plate against movement relative to the flanges, a spreading element for engaging and spreading one end portion of the wedge when moved to position between the flanges, and means coöperating with said spreading element for partly wrapping a portion of the wedge about the spreading element to anchor the wedge between the flanges.

4. In a rail joint, a fish plate having parallel laterally extending flanges formed longitudinally thereon, the lower one of said flanges having transverse seats, rail fastening pins insertible through the fish plate and into the seats, said pins having shoulders, a locking plate insertible between the flanges and above the pins, means depending from the plate for engaging the lower one of said flanges to hold the plate against removal from between the flanges, means depending from the plate for engaging the shoulders on the pins to hold said pins against withdrawal from the fish plate, a wedge insertible longitudinally between the flanges and above and back of the plate to hold said

plate against movement, said wedge having a split end, and means in the path of the split end of the wedge and integral with the flanges for spreading said wedge to anchor it between the flanges.

5. In a rail joint, a fish plate having parallel laterally extending flanges formed longitudinally thereon, the lower one of said flanges having transverse seats, rail fastening pins insertible through the fish plate and into the seats, said pins having shoulders, a locking plate insertible between the flanges and above the pins, means depending from the plate for engaging the lower one of said flanges to hold the plate against removal from between the flanges, means depending from the plate for engaging the shoulders on the pins for holding the pins against withdrawal from the fish plate, a wedge insertible longitudinally between the flanges and above and back of the plate to hold said plate against movement, said wedge having a split end, a spreading element in the path of the wedge for engaging and spreading one end portion of the wedge when inserted between the flanges, and means coöperating with said spreading means for partly wrapping a portion of the wedge about the spreading means to anchor the wedge between the flanges.

In testimony that we claim the foregoing as our own, we have hereto affixed our signatures in the presence of two witnesses.
